DESIGN FOR SHELF PAPER

Edward Karfiol, New York, N. Y.

Application March 28, 1933. Serial No. 47,619

Term of patent 14 years

To whom it may concern:

Be it known that I, EDWARD KARFIOL, a citizen of the United States, residing in New York, in the county of New York and the State of New York, have invented a new, original, and ornamental Design for Shelf-Paper, of which the following is a specification, reference being made to the accompanying drawing, forming part thereof, in which:

The figure represents a face view of a shelf-paper showing my new design, the lining on the drawing representing color.

I claim:

The ornamental design for shelf-paper as shown and described.

EDWARD KARFIOL.
